UNITED STATES PATENT OFFICE.

ROBERT M. DOWNIE, OF BEAVER FALLS, PENNSYLVANIA, ASSIGNOR TO KEYSTONE DRILLER COMPANY, OF BEAVER FALLS, PENNSYLVANIA, A CORPORATION OF PENNSYLVANIA.

DEEP-WELL PUMP.

1,401,681.

Specification of Letters Patent. Patented Dec. 27, 1921.

Application filed November 22, 1919. Serial No. 239,864.

To all whom it may concern:

Be it known that I, ROBERT M. DOWNIE, a citizen of the United States, residing at Beaver Falls, in the county of Beaver and 5 State of Pennsylvania, have invented a new and useful Deep-Well Pump, of which the following is a specification.

This invention has reference to deep well pumps and more particularly to means for 10 supplying air to the pump below the pump barrel, and its object is to lighten the load on the pistons by displacing part of the water, to cushion or render resilient the rising column of water, and to supply the 15 air chamber of the pump with air.

In accordance with the invention, air is supplied through a suitable pipe from the surface of the ground to a point which may be at the bottom of the pump barrel 20 so that the air enters the pump barrel below the piston, or in the case of a two-stroke pump, below the lower piston, and this air is distributed in the column of water entering the pump barrel so as to perme- 25 ate the water.

The invention is designed particularly for deep well pumps and provision is made whereby suction is established in the air pipe to cause the indrawing of the air. Such 30 suction is brought about by somewhat reducing the area of the water inlet to the pump barrel, so that the pump pistons produce an increased speed of flow into the pump barrel which is responded to by the 35 air in the air pipe, which latter is kept free from water by a suitable check valve.

The invention is particularly adapted to two-stroke deep well pumps, but may be used advantageously with single-acting deep 40 well pumps.

The air pipe may be a small affair, say a one-eighth or a one-quarter inch pipe, since the amount of air required is not large.

The invention will be best understood 45 from a consideration of the following detailed description taken in connection with the accompanying drawings forming part of this specification, with the understanding, however, that the invention is not confined to any strict conformity with the showing in the drawings, but may be changed and modified so long as such changes and modifications mark no material departure from the salient features of the

invention as expressed in the appended 55 claims.

In the drawings,

Figure 1 is an elevation of a deep well pump with the pump casing in section.

Fig. 2 is a longitudinal cross section, with 60 some parts in elevation, of the pump barrel.

Fig. 3 is a section on a larger scale than that of the preceding figures and limited to the check valve end of the pump barrel. 65

Fig. 4 is a top plan view of the check valve casing shown in Fig. 3 but omitting the water inlet check valve.

Fig. 5 is a section on the line 5—5 of Fig. 4. 70

Fig. 6 is a view similar to Fig. 3, but omitting some parts, and showing other parts in elevation which are indicated in section in Fig. 3, Fig. 6 showing a slightly different structure from that of Fig. 3. 75

Referring to the drawings, there is shown in Fig. 1 a well casing 1 in a well bore 2, which latter may be considered as representative of a deep well. Extending into the well is a tube 3 dropping from a working head 4, which need not be particularly described, since it forms no part of the invention. Branched off from the tube 3 is a pipe 5 including an air chamber 6, as is customary. At the lower end of the 85 tube 3 is a working barrel 7 containing pistons 8, 9 of the two-stroke or double-acting type. The invention is applicable to a single-stroke pump, but is particularly advantageous in a two-stroke pump. 90

At the lower end of the working barrel there is provided a connection 10 suitably shaped interiorly to receive a check valve 11 constituting the usual foot valve for the pump. The check valve connection 10 is 95 provided below the check valve 11 with a cross arm 12 which may be cast integral therewith, and this cross arm 12 has a longitudinal bore 13 extending from a lug 14 at one side of the connection 10 to a point 100 at or beyond the mid-point of the bar. Communicating with the bore 13 is a nipple 15, in the structure shown in Fig. 3, and this nipple carries a check valve 16, which may be of relatively small size, rising into 105 the suction chamber within the connection 10, and when the check valve 11 is present, rising into the interior of the latter. The

check valve 16 has a casing with numerous outwardly-directed small ports 17 and contains a valve member 18 which may be of the familiar ball type, although of course not confined to such particular type of valve. The valve 18 closes toward the bore 13, and communicating with the bore 13 through the boss or enlargement 14 is an air pipe 19 of small size, say made of one-eighth inch or 10 one-quarter inch pipe. This air pipe is carried up outside of the working barrel and inside of the well casing, to the surface of the ground, where it may be opened to the atmosphere through a valve 20 whereby the 15 amount of air permitted to flow through the pipe 19 may be controlled. This is the reason for carrying the pipe 19 to the surface of the ground, thus permitting an operator to readily adjust the amount of air 20 reaching the connection 10 through the check valve 16. The connection 10 is shown in the drawings as supporting a strainer 21, but as this is a customary practice in deep wells, no further description is necessary.

25 In the double stroke pump, when one piston is lifting its load on the upstroke, the other piston is returning. The two pistons thus relay each other, one taking up the load at the point where the other leaves off. 30 The upward speed of each piston varies from nothing at the beginning of the stroke to its point of highest speed, which is at quarter throw of the crank operating piston. The column of water, being rigid and non-compressible, has a variable and undesirable 35 impulse or impact upon each of the pistons and sucker rods at each stroke.

By the present invention, air is directed into the column of water, thereby cushioning 40 it. The impulsive motion of the water extends beyond the point of discharge and produces water hammering and vibration in any system of piping connected with the discharge. It is the purpose of the ordinary 45 air chamber incorporated in the discharge line to cushion the water column and avoid water hammering. While this is accomplished fairly well by the air chamber, such actions occurs only so long as the air chamber 50 is kept full of air. It has been found, however, in practice, that with deep well pumps the water readily absorbs the air from the air chamber and thereby soon destroys its efficiency. With the invention, 55 a constant supply of air is furnished, keeping the air chamber constantly replenished, this being because a small quantity of air is taken into the pump below the working barrel.

60 The arm or bar 12, across the water inlet to the pump, reduces the inflow area to such an extent that the action of the pistons 8 and 9 tends to produce a vacuum at the bar or arm 12. This tendency to produce a 65 vacuum causes the lifting of the check valve

member 18 and draws the contents of the pipe 19 into the pump barrel with the water. In case the well be normally filled with water for some distance above the working barrel, as is usually the case, the pipe 19, 70 known as a snifting pipe, may have water in it to the level of the water in the well. When the pump is started, this water will first be drawn out through the check valve 16 and thereafter the suction caused by the 75 pistons of the pump will at each stroke draw air down the snifting pipe and into the barrel. The volume of air required for different elevations, pressures and conditions, is readily regulated by the operation of the 80 valve 20 at the surface of the ground.

Upon entering the working barrel, the air is sprayed or disseminated in the rising volume of water, rendering it resilient instead of rigid, such resilience extending 85 throughout the entire length of the pump tubing. Besides rendering the column of water resilient, it also lightens the load upon the pistons. At the time when the pistons are traveling up at the greatest speeds the 90 occluded air in the water will compress momentarily and thus destroy any tendency to create a jarring on the pistons and sucker rods. The occluded air, when reaching the 95 opening of the air chamber, will automatically rise into the air chamber 6 and at all times keep the latter completely charged with air.

When once installed and the regulating valve 20 is adjusted, the whole device becomes 100 permanently automatic in its action.

In Fig. 6 is shown a check valve arrangement, for the lower end of the pump barrel, of slightly different design from that shown in Fig. 3, but in all essential particulars the 105 structures of Figs. 3 and 6 are alike, wherefore parts of Fig. 6 similar to those of Fig. 3, are designated by the same reference numerals with the exponent "a."

When the level of the fluid in the well is 110 below the pump barrel, a suction length of pipe may be added to the working barrel between it and the strainer.

What is claimed is:

1. A deep well piston lift pump having a 115 pump barrel, an air cushion chamber, and an air inlet pipe entering the pump below the pump barrel, whereby to furnish the pump with air in order to cushion hammering and to maintain a continuous air supply 120 in the air chamber.

2. A deep well lift pump having a pump barrel, a lifting piston structure therein, a foot valve at the lower end of the pump barrel, an air cushioning chamber above the 125 pump barrel, and an air inlet pipe communicating with the atmosphere at a relatively high point above the pump and entering the pump to discharge into the pump barrel below the foot valve and also provided with 130

a check valve opening toward the pump barrel.

3. A deep well piston pump having a barrel, with an air pipe entering the pump below the barrel, and said pump being also provided with constricting means at the water entering end of the barrel below the air inlet thereto.

4. A deep well piston pump with a pump barrel having constricting means for reducing the area of the water inlet to the pump, and an air duct, of which the constricting means forms a part at the air inlet to the barrel.

15 5. A deep well piston pump with a pump barrel having constricting means reducing the area of the water inlet to the pump, and an air duct leading from a high point outside of the pump barrel and entering the 20 pump through the constricting means with the discharge end of the air duct above and close to the constricting means.

6. A deep well piston pump with a pump barrel having constricting means reducing 25 the area of the water inlet to the pump, and an air duct leading from a high point outside of the pump barrel and entering the pump through the constricting means with the discharge end of the air duct above and 30 close to the constricting means, said air outlet including a check valve.

7. A deep well piston pump with a pump barrel having constricting means reducing 35 the area of the water inlet to the pump, and an air duct leading from a high point outside of the pump barrel and entering the pump through the constricting means with the discharge end of the air duct above and close to the constricting means, said air outlet in-

cluding a check valve, the outlet being 40 formed by numerous small openings pointing in different directions for disseminating the air through the moving mass of water.

8. A deep well piston pump having a pump barrel, and an air duct or pipe leading 45 from the surface of the ground where the pipe communicates with the atmosphere and terminating below the foot valve for the discharge of air into the foot valve under the suction of the pump and said pipe 50 having an accessible regulating valve at its upper end.

9. A deep well piston pump with a pump barrel, a cushioning air chamber at the discharge end of the pump, and an air pipe or duct leading from the atmosphere with the air at a pressure determined by the suction of the pump, and discharging into the lower end of the pump below the bottom of the pump barrel and the water level in the well. 60

10. A deep well piston pump with a pump barrel, a cushioning air chamber at the discharge end of the pump, and an air pipe or duct leading into the pump below the pump barrel and water level in the well, said 65 pump having constricting means for the water inlet to the pump barrel with said constricting means forming part of the air duct and the latter opening into the pump above and close to the constricting means. 70

In testimony that I claim the foregoing as my own, I have hereto affixed my signature in the presence of two witnesses.
